[57] CLAIM

[22] Filed: Sep. 20, 1978

The ornamental design for a bottle, substantially as shown and described.

DESCRIPTION

FIG. 1 is a side elevational view of a bottle showing my new design;

FIG. 2 is a top plan view of the bottle shown in FIG. 1;
FIG. 3 is a bottom view of the bottle shown in FIG. 1.
The side opposite that shown in FIG. 1 is the same in appearance as the side shown.
